UNITED STATES PATENT OFFICE.

DELOSS BORLAND, OF CHARLESTON, MISSISSIPPI, ASSIGNOR OF SEVEN-EIGHTHS TO
ABE ISENBERG AND MYER ISENBERG, OF CHARLESTON, MISSISSIPPI.

CHURN.

Application filed September 5, 1924. Serial No. 736,120.

The present invention relates generally to churns and the like and more particularly to an operating mechanism therefor. The principal object of the invention is to provide an operating mechanism of this nature which will be of an extremely simple, durable, and inexpensive structure, one which is efficient and reliable in operation, and well adapted to the purpose for which it is designed.

A particular object of the invention is to provide an operating mechanism of this nature which will be sanitary and which in operating the churn will not allow any oil or grease to come into contact with the churn thus eliminating the danger of such oil or grease being mixed with the contents of the churn.

Another particular object of the invention is to provide a device of this nature which is capable of operating in a simple and quiet manner providing for the long and useful life of the several parts of which the mechanism is composed.

A still further object of the invention is to provide a device of this nature which is useful in operating various different attachments.

With the above and numerous other objects in view as will appear as the description progresses, the invention resides in certain novel features of construction, and in the combination and arrangement of parts as will be hereinafter more fully described and claimed.

In the drawing:

Figure 1 is a vertical section taken through the device,

Figure 2 is another vertical section taken therethrough at right angles to that shown in Figure 3,

Figure 3 is a fragmentary elevation of the device showing particularly the mechanism in the lower portion thereof,

Figure 4 is a horizontal section through the device showing the lower portion thereof in top plan,

Figure 5 is a section on line 5—5 of Figure 2.

Referring to the drawing in detail it will be seen that C designates the cabinet generally which includes the lower portion A and the upper portion B. The upper portion B contains the churn while the lower

portion A contains the operating mechanism 55 therefor.

The lower compartment A is provided in its rear wall with a door 8 hinged as at 9 and normally held closed by latch mechanism 10. It is to be noted that the door 8 swings vertically the hinges being located at the bottom thereof. The door 8 functions as a platform and is provided in its side edges with notches 11 in which are pivoted legs 12. When the door is closed these legs will be completely confined within the notches but when the door is opened in a horizontal position as is disclosed to advantage in Figure 3 the legs 12 will be swung at right angles thereto thus supporting the door or platform. 70 The upper face or inner face of the door platform 8 is provided with a plurality of notched cleats 14 which are arranged in a circle for receiving screws or other projections 15 on the bottom portion of an ice-cream freezer 16' supported on the door platform when in its open position. This ice cream freezer is further supported and braced by a pivoted arm 16 hinged at 17 within the lower compartment and having a hooked end receivable in a keeper 18 mounted on the freezer 16'. The freezer is constructed with an enlarged sprocket wheel 19 which is also provided with a handle 20 in order that the same may be manually operated if necessary. A sprocket chain 21 is provided for the operation of this sprocket 19 and when not in use is adapted to be hung on a pair of hooks 23 depending from the upper wall of the lower compartment as 85 disclosed to advantages in Figures 1 and 2. 90

An electric motor 25 is mounted within the compartment A adjacent the front end thereof and is energized through a suitable cable. The pulley 27 of this motor has trained thereover a belt 28. A shaft 29 is journaled in the standards 30 rising from base 31 which is mounted on the bottom of compartment A. A pulley 32 is keyed to this shaft and has trained thereover the belt 28 so that upon operation of the motor 25 the shaft 29 is rotated. A pulley 34 is also keyed to an intermediate portion of the shaft 29 and is of a smaller diameter than pulley 32. 100

A base 35 is also mounted in the compartment A on the bottom thereof a distance from base 31 and extending parallel there-

with and under the upper compartment B. Standards 36 rise from the end of this base and have journaled therein a shaft 37 which is driven through a pulley 38 mounted thereon over which a belt 39 is trained, this belt also being trained over pulley 34 on shaft 29. It will thus be seen that upon operation of the motor 25 that the shaft 37 will be rotated through the intermediary of pulley 27, 10 belt 28, pulley 32, shaft 29, pulley 34, belt 39, and pulley 38. The journals of shafts 29 and 27 are lubricated by means of oil cups 40. The pulleys 32, 34 and 38 are keyed or fixed to their respective shafts by means of 15 set screws 42 passing through the collars thereof and engaging the shafts.

A sprocket 43 is mounted to the shaft 37 by means of one of the screws 42 and it is over this sprocket that the chain 21 is adapted to be trained when it is desired to operate the ice cream freezer heretofore described. A pulley 44 is fixed to the shaft 37 by one of the screws 42 and is adapted to have a belt 45 trained thereover which is 25 also trained over a pulley 46 mounted on a stub shaft 47 journaled in a bracket 48 provided inside the lower compartment in proximity to an opening 49 provided in the side of the lower compartment in order that an 30 end of a crank 50 may be passed therethrough and engaged with the end of the stub shaft. Thus this stub shaft may be manually rotated for rotation of shaft 37 through the intermediary of pulley 44 and 35 46 over which is trained the belt 45.

A crank 51 is mounted at each end of the shaft 37. These cranks are engaged with pitmen 52 which extend upwardly through slots 53 provided in the top of compartment 40 A up into compartment B. A churn 54 is positioned within the compartment B and may be of any preferred construction in the present instance consisting of the usual container having the agitator 55 located therein 45 and adapted to be reciprocated by a rod 56 which is slidable through a suitable closure 57.

A pair of inverted L-shaped standards 59 extend upwardly from the bottom of the compartment B and the upper or shorter arms 60 thereof support slide bars 61 which are of L-shaped structure the longer arms providing the slides whereas the lower and shorter arms 62 are engaged with intermediate 55 portions of the longer arms of standards 59. The standards 59 are braced by bars 63 which are attached to the bottom of compartment B in any suitable manner and their upper ends are fixed to the upper ends of 60 the standards by means of bolts 64 or in any other suitable manner. The standards 59 are also braced in respect to each other by cross rods 65. A head 66 is provided adjacent its ends with sliding journals 67 for receiving the slide bars 61 and trunnions 68

project beyond these slide bars into journals 67 positioned in the upper ends of the pitmen 52. The intermediate portion of this head 66 is fixed to the upper end of the rod 56 which is attached to the agitator 55.

From consideration of the device as thus far described it will be seen that upon rotation of the shaft 37 either by means of the motor or the manually operating mechanism that the cranks 51 will be rotated so as to reciprocate the pitmen 52 thus moving the head 66 up and down on the slide bar 61. This will cause the reciprocation of rod 56 and agitator 55 thus efficiently operating the churn. In this connection particular attention is called to the fact that all parts which require lubrication are so situated that the lubricant cannot possibly drift downwardly on the churn. The slide bars 61 are located, as is shown to advantage in Figure 85 2, to each side of the churn as are also the pitmen and the trunnions of the head 63. The churning operation, therefore, is absolutely sanitary as far as lubrication is concerned.

The shaft 29 is extended through one side wall of the lower compartment as will be seen by referring particularly to Figure 4, the extended portion of the shaft being designated specifically by the numeral 70. This 95 extension 70 has mounted thereon a pulley 71 located in a guard housing 72 on the outside of the lower compartment. A belt (not shown) may be trained over pulley 71 for the operation of various attachments.

In Figure 3 I have shown that the upper compartment B is provided in its front wall with a door 78 hinged at 78' and having its upper portion provided with a transparent panel 79 in order that the operation of the 105 churn may be partially seen without opening the door. By opening this door the churn may be easily placed in and out of compartment B and ready access be had to the operating parts within the compartment for lubricating and repair purposes.

It is preferable to mount the cabinet C on castors 80 or the like in order that it may be conveniently moved from place to place. It is my desire that the cabinet should have 115 an attractive design as is shown to advantage in Figures 1 and 2. The device is possessed of a simple, strong, and durable structure. The parts are of such a nature that they cannot very easily become out of order 120 and will operate in a noiseless and smooth manner. It is thought that the structure, operation and advantages of the invention should be now clearly understood without more detailed description thereof.

While the preferred embodiment of my invention has been described in detail with a certain degree of particularity, it will be understood that I do not wish to be limited to the particular construction set forth, since 130

various changes in the form, material, proportions, and arrangement of parts, and in the details of construction may be resorted to without departing from the spirit and 5 scope of the invention as hereinafter claimed or sacrificing any of its advantages.

I desire to call attention to Figure 5 which illustrates the ratchet wheel 80 of pulley 44 which is separate from its collar 81. A pivoted dog 83 on pulley 44 is engageable with the ratchet wheel so that the pulley 44 is free to remain stationary when the shaft 37 is operated by the motor, but made to rotate shaft 37 when operated by crank 50.

Having thus described my invention what I claim as new is:

1. In a device of the class described, a cabinet, a platform door hinged at its bottom to the bottom of the cabinet, said door 20 provided in its side edges with notches, legs pivotally mounted in said notches, means for supporting and holding an agitator device on the platform door, a shaft rotatably mounted in the cabinet, means in the cabinet

for operating the shaft, and a chain operable by the shaft for operating the agitator device. 25

2. In a device of the class described, a cabinet, a platform door hinged at its bottom to the bottom of the cabinet, means for supporting and holding an agitator device on the platform door when opened, a shaft rotatably mounted in the cabinet, means in the cabinet for operating the shaft, and a chain operable by the shaft for operating the 30 35 agitator device.

3. In a device of the class described, a cabinet, a platform door hinged at its lower end to the bottom of the cabinet, means for supporting said door in an open lowered position, means for holding an agitator device on said door when open, operating means in the cabinet, and means to operatively connect said operating means to said agitator device. 40 45

In testimony whereof I affix my signature.

DELOSS BORLAND.
